CLAIM

We claim the ornamental design for a nose and mouth shield for hockey helmet facemask, as shown and described.

DESCRIPTION

FIG. 1 is a perspective view of the nose and mouth shield for hockey helmet facemask of the present invention;

FIG. 2 is a front elevational view of the nose and mouth shield for hockey helmet facemask of the present invention;

FIG. 3 is top view of the nose and mouth shield for hockey helmet facemask of the present invention;

FIG. 4 is a bottom view of the nose and mouth shield for hockey helmet facemask of the present invention;

FIG. 5 is a left side elevational view of the nose and mouth shield for hockey helmet facemask of the present invention; and,

FIG. 6 is a right side elevational view of the nose and mouth shield for hockey helmet facemask of the present invention.
